CLAMSHELL BUCKET

William A. Olson, Wheatland, Mo.

Application July 21, 1947, Serial No. 762,411

3 Claims. (Cl. 37—185)

1

This invention relates generally to excavating equipment, and more particularly to a clamshell bucket comprising two main sections, each section having a scoop and a pair of lateral operating levers, a novel cable guard mounted on the shaft connecting the levers, and a complement of bucket-operating cables and pulleys, the general arrangement of the device and the construction of the scoop members including features of improved and novel character.

A primary object of this invention is to provide a clamshell bucket construction in which the cables are protected against undue wear, and prevented from snarling during the normal operation of the bucket.

Another object of this invention is to provide a centrally and vertically disposed cable guide of novel character secured to the shaft connecting the levers and extending upwardly to enclose operating cables.

Another object of this invention is to improve the construction of the scoop members in clamshell buckets of this character so as to facilitate the manufacture thereof and to make the more easily worn out portions replaceable.

Still another object of this invention is to provide a clamshell bucket which is relatively inexpensive and practicable to manufacture, extremely simple and convenient to use, and which is generally sturdy, efficient, and durable in service.

With these objects definitely in view, this invention resides in certain novel features of construction, combination and arrangement of parts and portions as will be hereinafter described in the specification, particularly pointed out in the appended claims; and illustrated in the accompanying drawings which form a material part of this application, and in which:

Figure 1 is a side elevational view of this improved clamshell bucket;

Figure 2 is another side elevational view, on a reduced scale, of this bucket;

Figure 3 is a top plan view of the bucket when the same is in fully opened position, the cables being shown as disposed when in taughtened position, the cable guard member being vertically disposed and the cable spider associated with the cables for opening the bucket, being shown immediately above the said cable guard member;

Figure 4 is a side elevational view of the bucket when in partially opened position, the fully opened position of the bucket being illustrated in dash lines, the figure being taken on line 4—4 in Figure 3;

Figure 5 is a transverse vertical sectional view of the cable guard member, the fair lead and the upper end of this cable member, together with portions of cables and the above mentioned cable spider, the figure being taken on the line 5—5 in Figure 3; and

Figure 6 is a transverse vertical sectional view, taken on the line 6—6 of Figure 3, the Figures 5 and 6 being both fragmentary in character.

2

Similar characters of reference designate similar or identical parts and portions throughout the specification and throughout the several views of the drawings.

5 Referring now to the drawings in detail, it will be noted that this improved bucket is constructed in two substantially similar sections, each section having a scoop, generally indicated by the numeral 10, dissimilar lever portions 12 and 14 pivoted together on the terminal portions of a shaft 16 and similar upwardly extending lever portions 18, a cable guard generally indicated by the numeral 20, and a complement of operating cables and pulleys as will be hereinafter described more fully.

20 Each scoop section 10 is comprised of an arcuate back plate 22, generally triangular side plates 24 which are secured to the said back plate by angles 26 and a replaceable nose plate 28 having terminal portions upwardly bent and marginally riveted to the side plates 24 and to the back plate 22, the general shape of the scoop being substantially conventional.

25 The lever 12 is constructed of two inflexible strap portions disposed in parallel relationship with lower end portions 30 riveted to the side plate 24, as indicated at 32, and upwardly extending portions 34 of unequal length straddling the corresponding said upwardly extending lever portions 18 and rigidly secured to the said portions 18, the bolts 36 being used to secure these parts together and simultaneously to mount a pair of spaced cross arms 38 to and between the upwardly extending portions of each of the levers 12, it being understood that the majority of the elements of this invention are provided in duplicate. The pair of levers 14 are each of single strap construction and the lower end 40 of each of these levers is secured by bolts or rivets to 30 the side plate 24 of the other section of the scoop 10. The upper end of the lever 14 is provided with a plate 42 and the lower edge 44 of this plate constitutes an abutment or stop which engages the end portion 46 of the outer strap member 45 of the double strap lever 12 when the bucket is fully open, this structure used to limit the opening of the bucket being most clearly shown in Figure 1. Auxiliary means to limit the opening of the bucket is provided on the other side 35 of the bucket and comprises a portion 48 at the lower end of the upwardly extending portion of the outer strap member, and the upper edge portion 50 of the corresponding side plate 24, this side plate being cut back so that the edge 50 contacts the portion 48 at the same time as the edge 44 contacts the portion 46.

40 The guard member, generally indicated at 20, comprises an inverted U-shaped tubular member, having the lower ends of the vertical arm portions thereof pivotally secured to the shaft 16, as indicated at 52 in Figure 2. The sides of these lower portions are extended to provide for terminal attachment of short shafts 54 which may

be of bolt form and to act as guards for pulleys 56 which are mounted on the shafts 54 between these guard portions which are best illustrated at 58 in Figure 4. The cross member 60 of the cable guard 20 is apertured as at 62, at each side thereof and these apertures register with the upper end of the tubular vertical arm portions of the cable guard. A fair lead comprised of parallel pairs of rollers 64 and 66 guides a cable 68 from an overhead drum or reel, not shown in the drawings, to the cross member 60, downwardly to the pulley 70 which is freely rotatably mounted in a bracket 72 pivotally mounted on the shaft 16. A plurality of sleeves 74 are secured on the shaft 16 to properly space the pivot members of the bracket 72 and the lower end members of the cable guard 20.

It will be noted that the cable 68 is entrained through the pulley 70, thence through one of the pulleys 76 which are rotatably mounted between the corresponding pairs of cross arms 38, and this cable extends from this pulley 76 to a pulley 78 which is one of a pair of similar pulleys rotatably mounted between the other pair of cross arms 38, the end of the cable 68 being ordinarily secured to an eye 80 which is rigidly secured to one of the cross arm members 38, as illustrated in Figure 3.

It should be noted that the cable 68 may be entrained about all four pulleys represented in the drawings at 76 and 78, the use of the extra pulleys having been found to be an advantage for certain types of work. A preferred method of mounting the pulleys 76 and 78 comprises the provision of vertically disposed supporting bracket members 82 which are rigidly secured to the cross arm members 38, and a cable guard plate 84 is provided on the outside of each of these pulley assemblies.

Obviously, the cable 68 is used to close the bucket and to lift the same, and two pairs of cables 86 are connected with the bucket to open the same. The cables 86 depend from a spider 88 which is operated by a single cable 90. The cables 86 are threaded through the apertures 62 downwardly through the vertical arms of the cable guard 20 and entrained around the pulleys 56 and thence outwardly around the pulleys 92 which are freely rotatably mounted in brackets 94 secured to the upper edges of the arcuate plates 22 of the scoops. The ends of the cables 86 are secured, as indicated at 96, to apertured members 98 integrally secured to the upper outer edges of the cross arms 38. It is preferred that each of the pulleys 76, 78 and 92 should be provided with a cable guide members of plate character as illustrated at 100.

The operation of this invention will be clearly understood from the foregoing description of the mechanical details thereof, when taken in connection with the above recitation of the objects sought to be achieved by this invention, but in recapitulation, it may be noted that the bucket will be suspended by the cable 68 and will be lowered and raised thereby, while the opening and closing of the buckets are provided for by upwardly tensioning of the cables 86 and by gravity, respectively. This method is exceptionally well adapted for use under conditions requiring the bucket to be lowered into the material sought to be moved with the scoop of the bucket closed, although the device is also well adapted for use when it is desirable to lower the bucket in open position and thereafter allow gravity to close the

bucket at the commencement of the elevation thereof.

It is believed that the foregoing description will enable persons skilled in the art to manufacture and use this invention and further description is therefore deemed unnecessary.

Though there has been shown a particular embodiment of this invention, this application is not limited to this particular embodiment, but it is desired to include in the scope of this invention, the construction, combination and arrangement of parts and portions substantially as set forth in the appended claims.

Having described the invention, what is claimed as new is:

1. A clamshell bucket comprising two main sections, each section having a scoop and a pair of lateral operating levers, a shaft extending through and between intermediate portions of said levers, the levers on each side of the bucket being pivoted upon terminal portions of said shaft, a cable guard secured on said shaft and normally vertically disposed, a bracket pivoted on said shaft, and a complement of bucket-operating cables and pulleys, said levers having connecting cross arms adjacent the ends of the levers remote from the scoops, said cables being terminally secured to said cross arms, and said cable guard extending upwardly beyond the cross arms when the scoops are closed together, said pulleys being mounted on the lower end of said cable guard, on said bracket, on the upper outer edges of said scoops, and on said cross arms, said cables including a pair of bucket-opening cables each entrained through one of said pulleys on the lower end of said cable guard and one of the pulleys on the upper outer edges of the scoops and terminally connected to the lever of the opposite scoop, and a bucket-closing and lifting cable entrained through a pulley on said bracket and through at least one of the pulleys on one of said cross arms and through at least one of the pulleys on the other cross arm and terminally secured to said one cross arm.

2. The device as defined in claim 1 wherein said cable guard is of inverted U-shape and has tubular vertical arms, the cross member of the cable guard being vertically apertured and having a fair lead for the bucket-opening and bucket-closing and lifting cables.

3. The device as defined in claim 1 wherein said cable guard is of inverted U-shape and has tubular vertical arms, the cross member of the cable guard being vertically apertured and having a fair lead, said fair lead guiding said bucket-opening and bucket-closing and lifting cables, and a spider connecting said bucket-closing and lifting cables with a single cable.

WILLIAM A. OLSON.
